VERNER F. DAVIS, OF ORANGE, NEW JERSEY.

HYGROSTAT.

1,088,972.

Specification of Letters Patent.

Patented Mar. 3, 1914.

Application filed February 15, 1910. Serial No. 544,042.

To all whom it may concern:

Be it known that I, VERNER F. DAVIS, a citizen of the United States, residing at Orange, in the county of Essex and State 5 of New Jersey, have invented certain new and useful Improvements in Hygrostats; and I do hereby declare the following to be a full, clear, and exact description of the invention, such as will enable others skilled 10 in the art to which it appertains to make and use the same, reference being had to the accompanying drawings, and to figures of reference marked thereon, which form a part of this specification.

15 This invention relates to a hygrostat or hygrometer which is adapted to maintain a percentage of humidity in the air operating by the expansion and contraction of rods which are subjected to wet and dry 20 bulb temperatures to control the expansion and contraction of such rods.

The apparatus is designed to be used in conjunction with means for humidifying the atmosphere and operates to cause or prevent 25 the admission of moisture into the air.

30 The apparatus comprises a wet rod and a dry rod and also a connecting means, the wet rod and the dry rod and the connecting means having the same coefficient of expansion and controlling, by their expansion, a certain percentage of humidity, which percentage is dependent on the relative lengths 35 of the wet rod, the dry rod and the connecting means which is preferably in the shape of a rod.

35 The apparatus consists of such rods connected by a lever so that the difference of the expansion between the wet rod and the dry rod actuates the lever to move the connecting means, the lever having an adjustable connection with one of the rods so that the lever when adjusted will maintain a constant difference between the wet bulb temperature corresponding to the per cent. humidity the machine maintained before adjustment and the actual wet bulb temperature. The percentage of humidity that is to be maintained is controlled by the relative lengths of the wet rod, the dry rod and 50 the connecting rod.

The invention further consists in so proportioning the rods and the bar that for about 10% of relative humidity the same bar will operate to control, in conjunction with the wet rod and the dry rod, the admission 55 of moisture to the chamber or receptacle in

which the apparatus is placed, the adjustment between the 10% being possible by a manually operated screw or similar device.

The invention is illustrated in the accompanying drawing, in which—

Figure 1 is a side view of the device connected with a humidifying means. Fig. 2 is an end view thereof, and Fig. 3 is a view from the other end. Fig. 4 is a section 65 through a portion of the device, illustrating one of the rods with means for keeping it wet.

The device comprises a suitable base 10 on which can be mounted a support 11 which 70 acts to hold the valves necessary for controlling the humidifying means, which support 11 has, projecting therefrom, two rods 12 and 13 which are made of material that is comparatively easily influenced by temperature changes, and I prefer to use hollow brass rods, although any other suitable metal can be employed, these rods 12 and 13 having the same coefficient of expansion, one of the rods, as 13, being maintained dry, and 80 the other rod, as 12, having a trough 14 arranged beneath it, this trough 14 being preferably attached to the support 11 and having a slotted opening 15 in its top. A cloth or other fabric 16 acts as a wick and by its 85 capillary attraction keeps the rod 12 wet for the most of its surface so that while the rods 12 and 13 are similarly affected by temperature, the rod 12, on account of its wet condition, will be influenced by the 90 amount of humidity in the air, affecting the evaporation of the moisture on the rod 12 so that if the air has a high percentage of humidity, evaporation from the moistening means and from the rod 12 will be slow and 95 the rod 12 will expand because it is allowed to become warmer. A low percentage of humidity in the air will cause a quick evaporation, consequently a lowering of temperature on the rod 12 and the rod 12 will 100 be contracted.

In a suitable bearing 17, on the end of the rod 12, is swiveled one end of a lever 18 which is pivoted at its other end, as at 19, to the end of a bar 20 which I prefer to 105 make of the same material as the rods 12 and 13 so that it will expand or contract with them under temperature changes. The lever 18 has an adjusting screw 21 therein which bears against the end of the rod 13 110 and may be supplied with an index finger 22 registering on a dial 23. The screw 21 is

used for adjusting the device to regulate the ratio between the lengths of the rods 12, 13 and 20. The bar 20 is connected, on the end opposed to the lever 18, to a valve lever 24 which is pivoted to the supports 25 and operates a valve 26 which in turn acts to actuate a relay lever 27 by means of the diaphragm 28, the relay lever 27, when operated, closing a valve 29. This construction of valve makes a positive, quick opening and closing valve, since the lever 24, when it opens the valve 26, permits the diaphragm to be supplied with compressed fluid which snaps the lever 27 to close the valve 29, and then the pressure fluid passes through the pipe 32 and the pipe 33 to operate the diaphragm valve 34 which in turn operates the valve 36. These valves are well known in the art of temperature regulation and the interior construction of the valve is not described herein, since the operation of them is well known to any one skilled in the art, the valves, however, operate to either admit or cut off fluid which enters through a pipe 30 from any suitable source of fluid pressure and passes through the pipe 31 and then through the valves and a second pipe 32 through the outlet pipe 33 and into a diaphragm 34, and acting against a spring 35. The fluid, when admitted, causes a closing of a valve 36 which is fed by a steam pipe 37, and when open, throws moisture into the air of the room or apartment, having it spread or scattered by a suitable sprinkler head 38, and in practice it is usual to drive the steam into the air by a blower 39.

It must be remembered that the difference between the wet bulb temperature and the dry bulb temperature becomes greater when the dry bulb temperature rises and the relative per cent. of humidity remains the same and it is necessary when the rods and the bar are made of material having the same coefficient of expansion for the bar 20 to compensate for this difference by the ratio of its length to that of the rods 12 and 13 when the rods 12 and 13 are of the same length and have the same coefficient of expansion. This ratio is determined by the following formula, when—

d_1 is the low dry bulb temperature.

w_1 is the low wet bulb temperature.

d_2 is the high dry bulb temperature.

w_2 is the high wet bulb temperature.

F is the product of $\frac{n}{k}$.

k is the distance between rods 12 and 13.

n is the distance between rod 13 and bar 20.

60 D is the length of rod 13 at d_1 .

M is the length of bar 20 at d_1 .

then,

$$65 M = D \left(1 + \left[1 - \frac{w_1 - w_2}{d_2 - d_1} \right] F \right).$$

It is further pointed out that the distances between the rods and the bar must be properly fixed in view of their relations to the coefficient of expansion and the lengths for the rods and the bar, it being not essential 70 that the product of $C \times L$ be the same, but that the equation

$$[(Y-X) \times F + Y] - Z,$$

be the same at any dry bulb temperature 75 when the relative humidity is the proper percentage. These proportions are evident from the following formula:

C is the coefficient of expansion.

L is the length.

T is the temperature.

X is the product of $C \times L \times T$ for rod 12.

Y is the product of $C \times L \times T$ for rod 13.

Z is the product of $C \times L \times T$ for bar 20 (the length of bar 20 is determined by formula above).

80 F is the product of $\frac{n}{k}$.

n is the distance between rods 12 and 13.

k is the distance between rod 13 and 90 bar 20.

It is not necessary that a bar 20 be of a different length for each per cent. of relative humidity at which the hygrostat is to operate, the variation being so slight that 95 the same bar will do for about 10 degrees, being adjustable by the screw 51, within these limits. For instance I will use one bar to operate between 26% and 35% relative humidity, another from 36% to 45% 100 relative humidity, and so on. This is consistent in view of the relative humidity at different temperatures both wet and dry bulb, as shown in the following table.

Rel. hum. is—	Dry bulb temp. is—	Wet bulb temp. is—	105
30%	30 F.	23 F.	
30%	60 F.	45 F.	
30%	90 F.	66.5 F.	
40%	30 F.	24.5 F.	
40%	60 F.	47.5 F.	
40%	90 F.	70.5 F.	
50%	30 F.	25 F.	
50%	60 F.	50 F.	
50%	90 F.	74 F.	110
60%	30 F.	25.5 F.	
60%	60 F.	51 F.	
60%	90 F.	76 F.	

115 The operation of the device is as follows: 120 When the humidity is low, evaporation from the wet rod 12 is rapid, the wet rod 12 contracts, pulls in on the end of the lever 18 which is fulcrumed on the screw 21, and pulls on the bar 20 to swing the lever 24 to 125 open the valve 26, and the valve mechanism does not operate to admit fluid under pressure from the pipe 30 to the pipe 33, and the spring 35 holds the valve in the steam pipe 37 open and steam is driven into the room 130

or compartment. It will be evident that this particular means of humidifying the atmosphere is not the only one that can be employed, and applicant does not wish to be understood as limiting himself to this means for moistening the air. As the percentage of humidity increases, the evaporation from the wet rod 12 becomes less rapid and the rod 12 therefore becomes warmer and expands, and in lengthening it operates, through the lever 18, the fulcrum 21 and the bar 20 to relieve the lever 24, and the spring 40 is allowed to act on the lever 24 to close the valve 23. The valve mechanism is then operated to permit fluid under pressure to pass from the pipe 30 into the pipe 33, the diaphragm valve 34 acts on the steam valve 36 and the supply of moisture is cut off. I maintain the water in the trough 14 by a suitable inlet pipe 41 and an outlet pipe 42, which pipes act to keep the water at the same level, but do not permit it to overflow. The amount of water admitted, of course, through the supply pipe is very small, since it is only necessary to supply what little is consumed in evaporation, and except for the first filling.

Having thus described my invention, what I claim is:—

1. Means for adjusting a valve of a humidifying apparatus consisting of a pair of rods made of material having the same coefficient of expansion, means for keeping one of the rods wet, a lever in pivotal relation with the rods, and a bar of material having the same coefficient of expansion as the pair of rods connecting the lever and the valve, the bar being proportioned in length so as to maintain its operativeness within a predetermined range of dry bulb temperature, the pair of rods and the bar being separated suitable distances to give the proper ratios of leverage to the lever.

2. Means for adjusting a valve of a humidifying apparatus consisting of a pair of rods having the same coefficient of expansion, means for keeping one of the rods wet,

a lever in pivotal relation with the rods, a bar having the same coefficient of expansion as the rods connecting the lever with the valve, and means on the end of one of the rods for adjusting the lever toward and from the end of the rod, the bar having its length and disposition so regulated that it maintains its operativeness within a predetermined range of dry bulb temperature, the pair of rods and the bar being separated suitable distances to give the proper ratios of leverage to the lever.

3. Means for adjusting a valve of a humidifying apparatus consisting of a pair of rods having the same coefficient of expansion, means for keeping one of the rods wet, a lever in pivotal relation with one of the rods, a bar in pivotal relation with the lever and connected with the valve, and a regulating screw in the lever and bearing on the other rod, the bar being disposed and proportioned so that it is operative for a predetermined range of dry bulb temperature, the pair of rods and the bar being separated suitable distances to give the proper ratios of leverage to the lever.

4. Means for adjusting a valve of a humidifying apparatus consisting of three rods, one end of the rods being connected by a lever, and means for keeping one of the rods wet, the wet rod and one of the dry rods having a fixed support, the third rod having one end connected to the valve to operate it, the rods having such lengths, coefficient of expansion, and being separated to give the proper ratios of leverage to the lever so as to operate the valve to keep the humidifying means at the point of operating with a given percentage of humidity regardless of temperature.

In testimony, that I claim the foregoing, I have hereunto set my hand this 10th day of February 1910.

VERNER F. DAVIS.
